(57) **CLAIM**

The ornamental design for an envelope, as shown and
described.

DESCRIPTION

FIG. 1 is a rear right bottom perspective view of an
envelope, showing my new design;

FIG. 2 is a top plan view of FIG. 1;

FIG. 3 is a front elevational view of FIG. 1;

FIG. 4 is a bottom plan view of FIG. 1;

FIG. 5 is a right side elevational view of FIG. 1, the left side
elevational view being a mirror image;

FIG. 6 is a rear elevational view of FIG. 1; and,

FIG. 7 is a rear elevational view of FIG. 1, with a top flap
folded back to the back wall.
